ENGINE-DRIVEN AIR SYSTEM FOR DIESEL ENGINES.

1,279,085.

Specification of Letters Patent. Patented Sept. 17, 1918.

Application filed April 3, 1916. Serial No. 88,686.

To all whom it may concern:

Be it known that I, GREGORY C. DAVISON, a citizen of the United States, and a resident of New London, in the county of New London, State of Connecticut, have invented 5 certain new and useful Improvements in Engine-Driven Air Systems for Diesel Engines; and I do hereby declare the following to be a full, clear, and exact description 10 of the invention, such as will enable others skilled in the art to which it appertains to make and use the same.

This invention relates to improvements in internal combustion engines of the type in 15 which one or more compressors are employed to feed air under pressure for coöperation with the oil-fuel fed to the fuel-spray valves on the engine cylinders. Heretofore it has been the practice to have such an engine 20 drive a single compressor, or else drive several compressors provided as a group with but a single intake and but a single discharge, the several compressors being arranged for use or disuse as a single group 25 with one compressor discharging into another before the air is led to the cylinders. In all such installations, disablement of the compressor or of any one of the group of compressors when such a group is employed, 30 instantly causes a cessation of the supply of compressed air to the fuel-spray valves and consequent stoppage of the engine.

The present invention involves the provision of an improved construction whereby 35 such interruption of the use of the engine will not occur whenever one of several compressors becomes disabled. A plurality of compressors are provided for supplying compressed air to the fuel-spray valves of 40 the engine and these are so arranged that either one may be employed independently of the other to supply the requirements of the engine. Preferably, both compressors would be employed together under normal 45 conditions but either may be used alone when the other is temporarily out of service so as to continue the operation of the engine without interruption.

In accordance with the preferred embodiment of the invention, the means by which 50 either compressor is rendered operative and other inoperative includes valves in the discharge conduits of the compressors which may be manipulated to connect either compressor to or disconnect it from the main

which carries the compressed air to the fuel-spray valves of the engine. The two compressors are preferably duplicates and arranged alongside each other and they are driven directly by the engine shaft. The 60 piping arrangement of the two compressors is such that each has its own separate and separately and individually controllable intake and its own separate and separately and individually controllable discharge. Also, 65 each compressor is preferably a two-stage one equipped with its own individual cooling means.

The invention therefore involves the provision of at least two working compressors 70 for simultaneous or alternative operation and permits a disabled compressor to be cut out either while the other compressor is left effective or just before the other compressor is cut in, according as a plurality of compressors or only one compressor was just previously working, all within the space of a few seconds, so that the disabled compressor may be repaired while the engine is 80 running and without stoppage of the engine due to a failure of the air-supply.

In the accompanying drawing, showing a preferred embodiment,

Figure 1 is an elevation of one side thereof; Fig. 2 is a partial elevation of the opposite side thereof; and Fig. 3 is a diagrammatic view showing certain of the parts of Figs. 1 and 2 in full lines and certain of these parts in dot-and-dash lines.

The reference numeral 1 indicates a bed- 90 plate or crank case for the engine. A three-cylinder engine 2 has a suitable engine shaft 3' extending the entire length of the bed plate. The engine shaft is provided with parallel offset cranks 3, in addition to the 95 cranks located in the engine crank pit for the pistons of the engine cylinders 2^a, the cranks 3 driving the compressor-pistons 3^a.

Each cylinder is provided with a fuel inlet valve 2^a; and each valve is suitably associated with means (not shown) for injecting oil-fuel. These valves are adapted to have spray-air fed thereto by means of connections 4^a leading from a main 4.

The twin compressors illustrated are each 105 provided with the usual large or initial compression cylinder 5 and the usual smaller or final compression cylinder 6. Each compressor is also equipped with automatic inlet valves at 5^a and 6^a (Fig. 2), automatic out- 110

let valves at 5^b and 6^b (Fig. 1), a connection 8 from the outlet valve 5^b to the inlet valve 6^a and a connection 9 from the outlet valve 6^b to the main 4.

5 Interposed in connections 8 and 9 of each compressor are suitable coils (Fig. 3) enclosed within a cooler 10 to serve that compressor. Coolers 10 are rendered effective by a common circulation of cooling water 10 through connections 10^a in the direction indicated.

Each connection 9, before it joins the main 4, has interposed therein a separately and individually adjustable shut-off cock 9^b.

15 A separate intake 11 is provided for each inlet valve 5^a, both intakes conveniently leading from a common suction header 11^a; and each of these intakes has interposed therein a separate shut-off cock 11^b. The 20 two cocks 11^b may, when desired, be opened and closed simultaneously by means of a control rod 12. If desired, the operating members of the cocks 11^b may be so connected to rod 12 that actuations of the rod 25 may open and close only one of the cocks 11^b, or open one of the cocks while closing the other.

During operation of the engine, either or both compressors may be operative. If it is 30 desired to use both compressors for normal service, opening the two shut-off cocks 9^b and the two shut-off cocks 11^b are the only operations required. If it is desired to use but a single one of the compressors for normal 35 service, it is only necessary to open the shut-off cocks 9^b and 11^b of the compressor to be used and close the shut-off cocks of the other compressor. In the case of the compressor thus functioning, during a half revolution of the engine shaft the compressor draws in atmospheric air through its intake 11 and intake valve 5^a into its larger compression cylinder 5. During the next half revolution of the engine shaft, the air thus 40 drawn in is compressed within the compressor's cylinder 5 and thence forced through its outlet valve 5^b into its connection 8 which passes through cooler 10. During the next half revolution of the shaft, the compressor draws this cooled and partially compressed air from connection 8 through inlet valve 6^a into the smaller compression cylinder 6. At the same time, an additional supply of atmospheric air for 45 initial compression is being drawn through the compressor's intake 11 and inlet valve 5^a into the larger compression cylinder 5. During the next half revolution of the shaft, the compressor further compresses and dis- 50 charges the air from its smaller compression cylinder 6 to the connection 9 which also passes through cooler 10, the finally compressed and cooled air being delivered to the fuel-spray valves 2^a through main 4. 55 At the same time, the air previously drawn

into the compressor's cylinder 5 is being initially compressed and discharged through its outlet valve 5^b into its connection 8 to pass through the cooler 10. Throughout the running of the engine, the compressor operates continually in this manner to deliver air under proper pressure to the fuel-spray valves 2^a.

If desired, only one of the compressors may be run normally. Then the control rod 75 12 may be permanently disconnected from the two cocks 11^b; or these cocks may be so adjusted and permanently connected to the rod 12 that when the rod is moved to open one cock 11^b the other cock 11^b is closed. 80 If the working compressor becomes disabled it may be cut out and the idle compressor cut in. The time required to close the shut-off cocks 9^b and 11^b of the disabled compressor and to open the cocks 9^b and 11^b of 85 the previously idle compressor, will not cause a cessation of the air supply. Even should the trouble in the disabled compressor cause the inlet valve 5^a to stick in open position, the lowering of the air pressure as the result of leakage at that valve will not lead to stoppage of the engines if either of the cocks 9^b and 11^b of the disabled compressor be closed, and the two cocks 9^b and 11^b of the other compressor opened promptly. There- 90 after the other of the two cocks 9^b and 11^b of the disabled compressor should be closed.

As to any compressor thus cut out for the purpose of making repairs thereto during 100 running of the engine, the piston of that compressor would continue to be driven by the engine shaft; but the cut-out compressor would not pump air, and the valves thereof could be removed, examined, repaired and replaced, and the compressor again cut in 105 at pleasure. It should be remembered that in practically every case of the accidental crippling of a compressor, the fault is in the valves or their connections, and not in the piston or its connections.

If desired, the normal operation may involve the use of both compressors. In anticipation of a possible future disablement of either compressor, the control rod 12 may be connected to the two cocks 11^b so that the 110 rod may be moved in one direction or the other to close the cock 11^b of the disabled compressor without closing the cock 11^b of the other compressor, or the rod 12 may be disconnected from the two cocks 11^b so that 115 the cock 11^b of the disabled compressor may be closed manually. Then if either compressor becomes disabled, that one may be cut out and the other temporarily burdened with all the work of feeding air to the fuel-spray 120 valves 2^a of the engine. The time required to close the shut-off cocks 9^b and 11^b of the disabled compressor will not cause a cessation 125 of the air supply. Even should the trouble in the disabled compressor cause the 130

inlet valve 5^a to stick in open position, the lowering of the air pressure as the result of leakage at that valve will not lead to stoppage of the engine if either of the cocks 9^b 5 and 11^b of the disabled compressor be closed. Thereafter the other of the two cocks 9^b and 11^b of the disabled compressor should be closed.

10 In a submarine boat, heavy oil internal combustion engines for many reasons have been the power plants generally employed for surface and awash running and the compressor and engine organizations heretofore employed in such power plants have possessed objectionable characteristics apparently impossible of avoidance. That these previous organizations often become disabled, sometimes rendering necessary an emergency utilization of the storage battery 15 plant aboard the submarine, a plant provided primarily for use during submerged navigation, is a fact that has been heretofore accepted as representing an unfortunate contingency which must always be present. The 20 present invention involves the provision of a simple and convenient mechanism whereby one of the causes of failure of the power-plant is practically eliminated. In this connection, it is to be remembered that within a 25 few seconds after the failure of the compressed air supply, the engines of a submarine boat will come to a dead stop, due to the absence of fly-wheels.

I claim:

- 35 1. An internal combustion engine organization comprising an engine of the Diesel type, a pair of air compressors driven thereby, and means for supplying compressed air to the inlet valves of the engine from either 40 one of the compressors at will, comprising manually-operated means for rendering either compressor operative and the other inoperative.
2. An internal combustion engine organization comprising an engine of the Diesel type, a pair of air compressors driven there-

by, and means for supplying compressed air to the inlet valves of the engine from either one of the compressors at will, comprising means, manually-operative while the engine 50 is running, to render either compressor operative and the other inoperative.

3. An internal combustion engine organization comprising an engine of the Diesel type, a pair of air compressors driven thereby, and means for supplying compressed air to the inlet valves of the engine from either one of the compressors at will, comprising independent air intakes for the compressors, valves in said intakes, and a control rod connected to said intake valves and adapted to close either one and open the other. 55

4. An internal combustion engine organization comprising an engine of the Diesel type, a pair of air compressors driven thereby, and means for supplying compressed air to the inlet valves of the engine from either one of the compressors at will, comprising independent air intakes for the compressors, valves in said intakes, and a control rod connected to the intake valves and adapted to close either one and open the other. 60

5. An internal combustion engine organization comprising an engine of the Diesel type, a pair of air compressors driven thereby, and means for supplying compressed air to the inlet valves of the engine from either one of the compressors at will, comprising independent air intakes for the compressors, valves in said intakes, separate discharge 70 connections for each compressor, valves in said discharge connections, and a control rod connected to the intake valves and adapted to close either one and open the other. 75

In testimony whereof I affix my signature. 80
